[57] CLAIM

The ornamental design for a video tape recorder, as
shown and described.

DESCRIPTION

FIG. 1 is a front, top and right side perspective view of
a video tape recorder showing our new design;
FIG. 2 is a view like FIG. 1 with the front operation
panel slide cover moved to closed position;
FIG. 3 is a front elevational view thereof with the front
operation panel slide cover moved to open position;
FIG. 4 is a top plan view thereof;
FIG. 5 is a rear elevational view thereof;
FIG. 6 is a bottom plan view thereof;
FIG. 7 is a left side elevational view thereof; and
FIG. 8 is a right side elevational view thereof.
